THREAD WINDING MACHINE

Horace L. Smith, Jr., Richmond, and Edward G. Mueller, Bon Air, Va., assignors to Hupp Corporation, Cleveland, Ohio, a corporation of Virginia

Filed Nov. 9, 1962, Ser. No. 236,572

8 Claims. (Cl. 242—46.4)

This invention relates to thread winding machines and, more specifically, to a collapsible arbor for thread winding machines.

Winding machines of the type to which the present invention relates are high speed, precision built machines adapted to wind natural and synthetic yarns on cops, cones, spools and tubes at speeds on the order of 50 to 150 yards per minute. Heretofore, the thread package supporting tube or other device has been mounted on a solid, generally wooden arbor fastened to the winding spindle of the thread winding machine. Solid arbors have proved unsatisfactory, especially when winding polypropylene, polyethylene, and similar polymeric synthetic fibers on paper tubes, since these fibers tend to compress the tube to such an extent that it is difficult to remove from the arbor.

To obviate this problem, collapsible arbors have been developed. Such arbors include one or more radially extensible tube supporting members such as rubber rings or garter springs each mounted on a pair of relatively movable supports. Moving the supports closer together expands the tube supporting members in gripping engagement against the inner surface of the thread package supporting tube. Moving the supports apart allows the tube supporting members to contract, permitting the tube and the thread wound upon it to be readily doffed from the arbor. In the prior art devices of this type, a compression spring is employed to force the supports together and to expand the tube gripping members and a lever is utilized to overcome the bias of the compression spring and move the supports apart and allow the expandable members to contract.

The prior art devices have the disadvantage that, if the lever is released by the operator, the compression spring will immediately move the supports together and expand the tube-supporting members, even though the tube has not been completely doffed. Consequently, the operator must keep one hand on the lever while removing the tube so that the tube-supporting members will remain contracted. Doffing of the thread package therefore becomes, at best, a relatively complicated, cumbersome procedure.

The novel collapsible arbor provided by the present invention, similar to the prior art devices, includes a pair of spaced apart garter springs each supported on two cooperating, relatively movable supporting members. The members in each pair are biased together by a compression spring. In contrast to the prior art devices, a novel cam and roller release mechanism operated by a rotatable knob is provided to spread the support members in each pair against the bias of the compression spring and allow the garter springs to collapse when it is desired to remove the package-supporting tube from the arbor. The release mechanism is so constructed that, once the operating knob is rotated to spread the supporting members to collapse the garter springs, it will retain them in this configuration without further manipulation by the operator. The operator thus has both of his hands free to doff the package.

Objects of the present invention include:

- (1) The provision of an improved collapsible arbor;
- (2) The provision of a collapsible arbor which is compatible with existent thread winding machines, and which may be readily incorporated in existent machines;

2

(3) The provision of a collapsible arbor for thread winding machines which will free the operator's hands for doffing a thread package from the winding spindle; and

(4) The provision of a collapsible arbor which is simple, rugged, and inexpensive to manufacture and maintain.

Further objects and other novel features of the present invention will become fully apparent from the appended claims and as the ensuing detailed description and discussion proceeds in conjunction with the accompanying drawing, in which:

FIGURE 1 is a perspective view of a thread winding machine equipped with a collapsible arbor constructed in accordance with the principles of the present invention;

FIGURE 2 is a section through the collapsible arbor taken substantially along line 2—2 of FIGURE 1; and

FIGURE 3 is a plan view of a cam employed in the collapsible arbor.

Referring now to the drawing, in which exemplary structure is shown, FIGURE 1 illustrates a thread winding machine 10 equipped with the novel collapsible arbor 12 provided by the present invention. Winding machine 10, which is disclosed in detail in copending application No. 138,166 filed September 14, 1961, by August J. Hambach for "Precision Winder" includes an electric motor (not shown) mounted on base plate 14 and surrounded by a housing 16 including removable panels 18 and 20 fastened in place by trunk latch 22.

The output shaft 24 of the electric motor (see FIGURE 2) extends horizontally from the interior of housing 16 through an aperture (not shown) in housing side wall 26 and through a conical shield 28 fastened to side wall 26 by screws 29.

Collapsible arbor 12, which is mounted on and fastened to motor output shaft 24, supports a cylindrical paper tube 30 on which thread 32 is wound to form a thread package 34. The winding machine motor simultaneously rotates tube 30 in the direction indicated by the arrow in FIGURE 1 and, through a gear gainer and a cam assembly (not shown) operatively connected to the opposite end of the motor output shaft, reciprocates a tubular traverse rod 36 along tube 30. Traverse rod 36 pivotally supports an arm 38 on which are fixed a guide 40 and a thread guide assembly 42 which guides thread 32 onto tube 30 to form thread package 34.

Referring now to FIGURE 2, collapsible arbor 12 includes a tube 44 mounted on winding motor output shaft 24. One end of tube 44 is supported by winding motor output shaft 24 and abuts an annular shoulder 46 formed on the shaft adjacent the outer end of conical shield 28. The opposite end of tube 44 is supported by the outboard end 48 of motor output shaft 24. Tube 44 is rotatably fixed to winding motor output shaft 24 by a setscrew 50 which extends through a circular backing plate 52 fixed to the inner end of tube 44 as by welding and through tube 44 into a flat 54 cut in the motor output shaft.

The reduced diameter end portion 56 of the backing plate supports the inner end of paper tube 30 which abuts an annular shoulder 58 provided by an increased diameter portion 60 of the backing plate. A triangularly sectioned, sharp edged blade 61 fixed to the periphery of backing plate 52 prevents tube 30 from rotating relative to the backing plate. Paper tube 30 is also supported by a pair of collapsible garter springs 62 and 64 which surround tube 44 at approximately its midpoint and adjacent its outer end. Garter springs 62 and 64 are circularly formed coil springs. Garter spring 62 is supported in concentric relation to tube 44 by a pair of cooperating spring supporting discs 66 and 68. Garter spring 64 is similarly supported by a spring supporting disc 70 and by chamfered, hollow, cylindrical sleeve 72.

Spring supporting discs 66, 68, and 70, which are substantially identical, each comprise a flat, annular, main

body portion 74 and an annular flange 76 providing a conical spring supporting surface 78. Spring supporting discs 66 and 70 are fixed to tube 44 as by welding or brazing. Spring supporting disc 68, which cooperates with disc 66 to support garter spring 62, is brazed to three elongated rods 80 equiangularly spaced around the periphery of tube 44 (only one of which is shown) which extend through appropriate apertures (not shown) in spring supporting discs 66, 68, and 70 and cylindrical sleeve 72 along and substantially parallel to tube 44. At the inner end of arbor 12, rods 80 extend through apertures 82 in an annular spring retaining disc 84 slidably mounted on tube 44. Stop members such as Truarc snap rings 86, inserted in grooves (not shown) formed adjacent the inner ends of rods 80, prevent the rods from being withdrawn through disc 84. The outer ends of rods 80 are fixed, as by welding, to sleeve 72.

Sleeve 72 has an outside diameter approximately equal to the maximum diameter of spring supporting discs 66, 68, and 70. An inclined annular flange 88, formed at the inner end of sleeve 72, provides a conical supporting surface 90 for garter spring 64. At the inner edge of flange 88, an integral, annular, sleeve supporting flange 92 projects inwardly to tube 44. Rods 80 extend through and are welded to sleeve supporting flange 92.

The function of the collapsible arbor structure thus far described is as follows: cam sleeve 72 may be moved to the right, drawing with it rods 80 and spring supporting disc 68. This moves apart the cooperating spring supporting surfaces 78 of discs 66 and 68 and the cooperating spring supporting surfaces 78 of spring supporting discs 70 and 90 of sleeve 72, allowing garter springs 62 and 64 to contract. Tube 30 may then be slid over the garter springs and the reduced diameter end portion 56 of backing plate 52 and butted against annular shoulder 58. Sleeve 72 is then moved to the left, moving rods 80 and spring supporting disc 68 in the same direction. This moves the two pairs of cooperating conical spring supporting surfaces closer together, forcing garter springs 62 and 64 outwardly against the internal surface 94 of tube 30 to retain it on the arbor. After the winding of thread package 34 is completed, sleeve 72 is again moved to the right collapsing the garter springs and allowing the thread package to be readily doffed even though paper tube 30 has been substantially compressed by the thread wound upon it.

Rods 80, spring supporting disc 68, and spring supporting sleeve 72 are biased to the left to maintain garter springs 62 and 64 in their expanded, tube supporting configuration by a coil compression spring 96 which surrounds tube 44 and extends between the main body portion 74 of spring supporting disc 66 and disc 84. To move rods 80, spring supporting disc 68, and sleeve 72 to the right to collapse garter springs 62 and 64 and permit the removal of the completed thread package, a cam assembly indicated generally by reference character 98 is provided.

Cam assembly 98 includes an actuator shaft 100. Shaft means such as a dowel pin fixed to actuator shaft 100 or the reduced diameter end portion 101 of shaft 100 is rotatably mounted in a blind bore 102 drilled in the outer end of winding motor output shaft 24. Fixed to the outer end of actuator shaft 100 is a knurled operating knob 104. A conventional thrust bearing 106, surrounding actuator shaft 100 and extending between the outer end of tube 44 and the inner end of actuator shaft 100 insures that operating knob 104 can be rotated relative to tube 44 without binding. Actuator shaft 100 supports a pair of cam rollers 109 and 110 rotatably mounted on opposite sides of the shaft by a pin 112 which extends through bores 114 and 116 in the rollers and through a transversely extending aperture 118 in the actuator shaft.

Cam rollers 109 and 110 cooperate with an annular cam surface 120 formed on the inner face of an annular

cam 122 which surrounds actuator shaft 100. Cam 122 is supported by sleeve 72 which extends over a reduced diameter portion 123 of the cam forming an annular, sleeve receiving recess 124 and is rigidly fixed to the cam as by brazing. Cam surface 120 is divided into two equal area portions so arranged that cam rollers 109 and 110 follow identical paths when knob 104 is rotated and therefore exert a force on cam 122 which is symmetrical relative to the longitudinal centerline of winding motor output shaft 24. Each cam surface portion slopes upwardly from a low point or dwell 126 to a high point or rise 128. Each rise 128 and the adjacent dwell 126 are connected by a shoulder 130 extending substantially normal to cam surface 120. When knob 104 is rotated in the direction indicated by the arrow in FIGURE 2, rollers 109 and 110 ride up the sloping cam surface portions from dwells 126 to rises 128. Since rollers 109 and 110 are prevented from moving toward winding motor output shaft 24 by thrust bearing 106 and the outer end of tube 44, cam 122 is forced to the right, pulling sleeve 72, rod 80, and cam disc 68 to the right against the bias of spring 96.

As was explained above, this movement of cam disc 68, rod 80, and sleeve 72 permits garter springs 62 and 64 to contract, allowing the operator to doff the completed thread package 34 and insert a new tube 30.

Arcuate depressions 132, formed in cam surface 120 at rises 128, retain rollers 109 and 110 on rises 128 until knob 104 is rotated by the operator. Garter springs 62 and 64 therefore remain collapsed until knob 104 is again rotated, freeing both of the operator's hands for removal of the completed thread package and insertion of a new tube. After the new tube is in place, knob 104 is again rotated in the direction of the arrow, allowing rollers 109 and 110 to ride off rises 128 and drop over shoulders 130 onto dwells 126. Compression spring 96 then moves rods 80, spring supporting disc 68, and cam housing 72 to the left, expanding garter springs 62 and 64 outwardly against inner wall surface 94 of tube 30 to secure the new tube 30 in place.

The invention may be embodied in other specific forms without departing from the spirit or essential characteristics thereof. The present embodiment is therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by Letters Patent is:

1. A collapsible arbor for thread winding machines, comprising:
  - (a) first and second resilient, radially expandable, spaced apart package retaining members;
  - (b) first and second retaining member supporting means;
  - (c) means for simultaneously varying to substantially the same degree the effective diameters of said first and second retaining member supporting means;
  - (d) means normally maintaining the effective diameters of said first and second supporting means at a maximum; and
  - (e) means having a cooperating cam and roller spaced outboard of both package retaining members for simultaneously reducing the effective diameters of said first and second supporting means to and maintaining them at a minimum and including means solely in said collapsible arbor for locking said first and second retaining member supporting means with their effective diameters at a minimum to maintain the first and second package retaining members collapsed.
2. A collapsible arbor for thread winding machines, comprising:

- (a) a winding spindle receiving sleeve;
- (b) means for detachably fixing said sleeve to a winding spindle received therein;
- (c) a pair of spaced apart garter springs surrounding said sleeve;
- (d) a pair of supporting members providing two annular, inclined, facing supporting surfaces spacing each of said springs from said sleeve;
- (e) means fixing one of each pair of supporting members to said sleeve;
- (f) an operating member;
- (g) means fixing the other of each pair of supporting members to said operating member;
- (h) means operatively engaging said operating member and biasing the members in each pair of supporting members toward each other to expand said garter springs; and
- (i) release means fixed to one end of said operating member for moving the members in each pair of supporting members apart against the influence of said biasing means to collapse said garter springs and for retaining said garter springs in said collapsed configuration, said release means including means solely in said collapsible arbor for locking said supporting members apart to maintain said garter springs collapsed.

3. The collapsible arbor as defined in claim 2, including an annular backing plate fixed to said sleeve in longitudinally spaced relationship to said garter ring supporting members, said backing plate including a cylindrical tube supporting portion and an annular flange for locating a tube longitudinally of said sleeve.

4. A collapsible arbor for thread winding machines, comprising:

- (a) a winding spindle receiving sleeve;
- (b) means for detachably fixing said sleeve to a winding spindle received therein;
- (c) a pair of spaced apart garter springs surrounding said sleeve;
- (d) a pair of supporting members providing two annular, inclined, facing supporting surfaces spacing each of said springs from said sleeve;
- (e) means fixing one of each pair of supporting members to said sleeve;
- (f) an operating member;
- (g) means fixing the other of each pair of supporting members to said operating member;
- (h) means operatively engaging said operating member and biasing the members in each pair of supporting members toward each other to expand said garter springs;
- (i) release means fixed to one end of said operating member for moving the members in each pair of supporting members apart against the influence of said biasing means to collapse said garter springs and for retaining said garter springs in said collapsed configuration;
- (j) one of said spring supporting members comprising an enlarged diameter sleeve having an annular flange at one end thereof surrounding said spindle receiving sleeve, said sleeve being slidable on said spindle receiving sleeve; and said release means including:
- (k) shaft means fixed longitudinally of and rotatable relative to said spindle receiving sleeve;
- (l) a rotatable operating member fixed to and axially aligned with said shaft means;
- (m) a circular cam providing an annular cam face slidably mounted on a shaft portion of said rotatable operating member and supporting the end of said enlarged diameter sleeve opposite said flange;
- (n) a pin extending transversely through the operating member shaft portion; and
- (o) cam rollers journaled on the end portions of said pin and cooperating with said cam to move said

enlarged diameter sleeve longitudinally of said spindle receiving sleeve.

5. The collapsible arbor as defined in claim 4, including a thrust bearing journaled on said shaft means and extending between said spindle receiving sleeve and said operating member shaft portion.

6. A collapsible arbor for thread winding machines, comprising:

- (a) a winding spindle receiving sleeve;
- (b) means for detachably fixing said sleeve to a winding spindle received therein;
- (c) a pair of spaced apart garter springs surrounding said sleeve;
- (d) a pair of supporting members providing two annular, inclined, facing supporting surfaces spacing each of said springs from said sleeve;
- (e) means fixing one of each pair of supporting members to said sleeve;
- (f) an operating member;
- (g) means fixing the other of each pair of supporting members to said operating member;
- (h) means operatively engaging said operating member and biasing the members in each pair of supporting members toward each other to expand said garter springs including:
- (i) a spring retaining member slidably mounted on said sleeve;
- (j) a stop member between the end of said operating member and said retaining member and operatively connecting said operating and spring retaining members; and
- (k) release means fixed to one end of said operating member for moving the members in each pair of supporting members apart against the influence of said biasing means to collapse said garter springs and for retaining said garter springs in said collapsed configuration.

7. A collapsible arbor for thread winding and like machines, comprising:

- (a) a winding spindle receiving sleeve;
- (b) means for detachably fixing said sleeve to a winding spindle received therein;
- (c) a pair of spaced apart expansible thread package supports surrounding said sleeve;
- (d) a pair of supporting members providing two annular, inclined, facing supporting surfaces spacing each of said thread package supports from said sleeve;
- (e) means fixing one of each pair of supporting members to said sleeve;
- (f) an operating member;
- (g) means fixing the other of each pair of supporting members to said operating member;
- (h) means operatively engaging said operating member and biasing the members in each pair of supporting members toward each other to expand said thread package supports including:
- (i) a package support retaining member slidably mounted on said sleeve;
- (j) a stop member between the end of said operating member and said retaining member and operatively connecting said operating and package support retaining members; and
- (k) release means fixed to one end of said operating member for moving the members in each pair of supporting members apart against the influence of said biasing means to collapse said package supports and for retaining said package supports in said collapsed configuration.

8. A collapsible arbor for thread winding machines, comprising:

- (a) a winding spindle receiving sleeve;
- (b) means for detachably fixing said sleeve to a winding spindle received therein;
- (c) a pair of spaced apart expansible thread package supports surrounding said sleeve;

- (d) a pair of supporting members providing two annular, inclined, facing supporting surfaces spacing each of said package supports from said sleeve;
- (e) means fixing one of each pair of supporting members to said sleeve;
- (f) an operating member;
- (g) means fixing the other of each pair of supporting members to said operating member;
- (h) means operatively engaging said operating member and biasing the members in each pair of supporting members toward each other to expand said package supports;
- (i) release means fixed to one end of said operating member for moving the members in each pair of supporting members apart against the influence of said biasing means to collapse said package supports and for retaining said package supports in said collapsed configuration;
- (j) one of said package support supporting members comprising an enlarged diameter sleeve having an annular flange at one end thereof surrounding said spindle receiving sleeve, said sleeve being slidable on said spindle receiving sleeve; and said release means including:

5 10 15 20

- (k) shaft means fixed longitudinally of and rotatable relative to said spindle receiving sleeve;
- (l) a rotatable operating member fixed to and axially aligned with said shaft means;
- (m) a circular cam providing an annular cam face slidably mounted on a shaft portion of said rotatable operating member and supporting the end of said enlarged diameter sleeve opposite said flange;
- (n) a pin extending transversely through the operating member shaft portion; and
- (o) cam rollers journalled on the end portions of said pin and cooperating with said cam to move said enlarged diameter sleeve longitudinally of said spindle receiving sleeve.
